Raymond L. Adolf, Galesburg, Ill., assignor to
Raymond L. Adolf and Victor E. Groppe, a
partnership doing business as Wee Folks Furni-
ture Company, St. Louis, Mo.

Application October 15, 1945, Serial No. 122,838

Term of patent 14 years

(Cl. D33—19)

To all whom it may concern:

Be it known that I, Raymond L. Adolf, a citizen of the United States and a resident of Galesburg, in the county of Knox and State of Illinois, have invented a new, original, and ornamental Design for a Combined Nursery Bathstand and Utility Cabinet, of which the following is a specification, reference being had to the accompanying drawing, forming part thereof.

Fig. 1 is a front perspective view of a combined nursery bathstand and utility cabinet, showing my new design.

Fig. 2 is a perspective view showing the top

raised, the central tier of drawers and side doors on either side thereof opened and the shelves above said tier and one of the side compartments projecting outwardly; and

Fig. 3 is a plan view with the top shown in raised position.

The side not shown in Figs. 1 and 2 is the same as the side appearing therein.

I claim:

The ornamental design for a combined nursery bathstand and utility cabinet, substantially as shown and described.

RAYMOND L. ADOLF.
